CLAIM

The ornamental design for an inflatable pad with cross straps as shown and described.

DESCRIPTION

FIG. 1 is a back perspective view showing our new design; FIG. 2 is a front elevational view thereof; FIG. 3 is a back elevational view thereof; FIG. 4 is a right side elevational view thereof; FIG. 5 is a left side elevational view thereof; FIG. 6 is a top plan view thereof; and, FIG. 7 is a bottom plan view thereof.

The broken lines in the drawings depict portions of the inflatable pad with cross straps that form no part of the claimed design.
